US00D991846S

(12) **United States Design Patent** (10) Patent No.: **US D991,846 S**
(45) Date of Patent: **** Jul. 11, 2023**

(54) **VEHICLE OUTER GRILLE**

(71) Applicant: **GM GLOBAL TECHNOLOGY OPERATIONS LLC**, Detroit, MI (US)
(72) Inventor: **Kirk D. Bennion**, Macomb, MI (US)
(73) Assignee: **GM Global Technology Operations LLC**, Detroit, MI (US)

(**) Term: **15 Years**

(21) Appl. No.: **29/812,099**

(22) Filed: **Oct. 19, 2021**

(51) LOC (14) Cl. **12-16**
(52) U.S. Cl.
USPC **D12/163**

Assistant Examiner — Suzanne E Tisdell

(57) **CLAIM**

The ornamental design for a vehicle outer grille, as shown and described.

DESCRIPTION

FIG. 1 is a front and left perspective view of a vehicle outer grille showing my new design;

FIG. 2 is a front elevation view of the vehicle outer grille of FIG. 1;

FIG. 3 is a left elevation view thereof;

FIG. 4 is a right elevation view thereof;

FIG. 5 is a back elevation view thereof;

FIG. 6 is a top view thereof; and,

FIG. 7 is a bottom view thereof.

The broken lines in the drawings depict portions of the vehicle outer grille that form no part of the claimed design.

1 Claim, 7 Drawing Sheets
